CLAIM

The ornamental design for a portable hard drive cartridge, as shown and described.

DESCRIPTION

FIG. 1 is a perspective view of a portable hard drive cartridge illustrating the new design;

FIG. 2 is a front view thereof;

FIG. 3 is a rear view thereof;

FIG. 4 is a top side view thereof;

FIG. 5 is a bottom side view thereof; and,

FIG. 6 is a left side view thereof; where a right side view is not presented, as it is a mirror image of the left side view.

In FIGS. 1-6 the broken lines showing stacking feet and recesses are for illustrative purposes only and form no part of the claimed design.

In FIG. 3 the broken lines showing a data access port are for illustrative purposes only and form no part of the claimed design.
